UNITED STATES PATENT OFFICE.

CHARLES MENSFORTH PATTISON, OF PENTRE, WALES.

APPARATUS FOR GENERATING COMBUSTION PRODUCTS UNDER PRESSURE.

1,331,523.

Specification of Letters Patent. Patented Feb. 24, 1920.

Application filed November 27, 1918. Serial No. 264,432.

To all whom it may concern:

Be it known that I, CHARLES MENSFORTH PATTISON, a subject of the Kingdom of Great Britain, residing at 2 Park View, Lelli, 5 Pentre, in the county of Glamorgan, Wales, (formerly of Britannia villa, Pengam, Monmouthshire, Wales,) have invented a certain new or Improved Apparatus for Generating Combustion Products Under Pressure, of 10 which the following is a specification.

This invention relates to a new or improved apparatus for generating combustion products under pressure, such apparatus comprising two or more explosion chambers 15 each having means of ignition of the fuel charges, a valve controlled chamber which receives the products of combustion, and a compressed air chamber, all of which are adapted for the supply of the charge and the 20 timing of the ignition to be automatically controlled by the pressures in the explosion and compressed air chamber, in connection with which apparatus it is also proposed to mix the air under pressure from the compressed air chamber with the fuel to form 25 the vaporized charge and to utilize the gases remaining in any one combustion chamber after the main products of combustion have passed to the receiving chamber for the 30 operation of an air compressor for obtaining the required pressure in the compressed air chamber, as also in restarting the apparatus to use the pressure in the compressed air chamber and also the pressure in the receiving 35 chamber for starting the action of the air compressor.

The air in the compression chamber is preferably heated by passing the compressed air around the valves admitting the gases to 40 the receiving chamber, or around the parts adjacent thereto, while any excess of predetermined maximum pressure in the receiving chamber is adapted to stop the supply of fuel and the ignition, the whole apparatus 45 being so arranged as to have an automatic action.

In order that this invention may be clearly understood and readily carried into practice, reference may be had to the appended sheets of explanatory drawings, 50 upon which:

Figure 1 is a longitudinal sectional elevation of the apparatus in diagram.

Fig. 2 is an enlargement of certain parts 55 of Fig. 1 for the purpose of rendering such parts more clearly understandable.

Fig. 3 is a further enlargement of one of the parts shown in Fig. 1.

Fig. 4 is an elevation in diagram of the one end of the apparatus shown in Fig. 1, 60 looking in the direction of the arrow X.

Fig. 5 is an elevation of the other end of the apparatus looking in the direction of the arrow Y.

In a convenient embodiment of this invention three explosion chambers D in the form of tubes are fitted within a single receiving chamber R, such tubes being adapted to receive the fuel charges and be fired successively, the supply of the charges and the firing being automatically controlled by the pressure in the air compression chamber A, R, as follows:—Oil fuel is supplied under pressure from the tank T through the pipe C¹ to the aperture C¹³ in the piston C², which forms part of the carbureter C which takes in a charge of fuel, the quantity of the charge being regulated while the piston C² is at rest at the bottom of the chamber C⁴, by the air release C³, which release comprises 75 a restricted adjustable outlet, so that when the piston C is lifted, the oil gravitates to the bottom of the chamber C⁴, and the fuel inlet C¹² is closed.

Upon the downward stroke of the piston C², the oil is forced into the vaporizer V through pipe V' by hot compressed air from the chamber A, R, through pipe A, R¹, the air passing through port C⁵ in piston C² down the passage C⁸ in piston rod C⁶ and 80 into the vaporizer V where it passes through the three gauze partitions V², V³ and V⁴ by which the oil is thoroughly vaporized before it reaches the explosion tube D.

When the explosion tube D is charged 95 with the fuel mixture produced by the aforementioned operation the piston valve D¹ is lifted by the pressure of the charge, which passes down the passage D¹³ and through a restricted adjustable aperture at D⁸ into the 100 chamber D¹⁴, thus closing port D and opening port D⁹, which allows the air pressure from the compressed air chamber A, R, to operate on the piston C⁷ of the carbureter, this being effected by the valve D¹ connecting the port D⁵ of the pipe D⁶ from the compressed air chamber with the port D⁹ of the pipe D⁴ to the carbureter cylinder at the underside of the piston C⁷ which is attached to the piston rod C⁶ the action of the air pressure being such as to force up the piston C⁷, thus lifting piston rod C⁶, thereby clos- 110

- ing valve C^2 , and then lifting piston C^2 which closes port C^6 . The rod H of the piston rod C^6 upon the piston reaching its maximum height operates the trip magneto lever 5 F which fires the charge in tube D by means of the sparking plug P . During the above described operation, the piston valve D^1 has closed the port D^3 shutting off the air pressure from the piston C^7 , an air relief valve 10 C^{11} being fitted in chamber C^{10} which allows the air pressure to escape from the bottom of piston C^7 and allows the piston C^7 to return for a repeat operation for the next charge.
- 15 After the explosion the burnt gases pass from the explosion chamber D through the valve chamber B in the course of which the valves B^1 and B^2 are lifted and the gases enter the receiving chamber R where they are retained under high pressure to be used expansively as required.
- 20 The ignited gases which are left in the explosion chamber D pass through piston valve E , and back pressure valve E^1 to an air compressor A , which is thus driven for the supply of compressed air to the compressed air chamber A , R , the compressed air being passed through jackets B^3 of the valve chambers B , so as to have a cooling 25 effect on the valve chambers, and at the same time heat the supply of air to the air receiver, so as to increase its volume and render assistance in the vaporization of the fuel.
- 30 The three explosion chambers D which are in the form of tubes are fitted within a single receiving chamber R , such tubes being adapted to receive the fuel charges and be fired successively, for which purpose they 35 are governed as hereinafter set forth by the piston valves E which are closed by the pressure of the burnt gases from the explosion which has taken place in the preceding chamber, the arrangement being such that 40 the burnt gases in say the explosion chamber No. 2, cannot be discharged into the air compressor A until the burnt gases in explosion chamber No. 1 have been discharged, and so on, while the piston valve D^1 cannot open the port D^2 to admit a 45 fresh charge until the explosion chamber is fully exhausted, and thus releases the pressure from under the piston valve D^1 . For closing the piston valve E by the pressure 50 of the burnt gases of the explosion in the preceding explosion chamber, the explosion chamber indicated for example in Fig. 5 by D^9 is connected to the under-side of the piston valve E^8 by the pipes E^4 , the explosion chamber D^{10} being similarly connected by the pipes E^5 to the chamber below the piston valve E^9 .
- 55 For the purpose of initially starting the apparatus the pipes E^4 , E^5 , and E^6 are respectively connected with the previously

charged air compression chamber A , R , by pipes A^1 , A^2 , A^3 and A^4 , the three two-way valves E^2 which for operation are connected together by a rod being used by the operator for starting the apparatus by shutting off the connection between the explosion chambers D and the piston valves E , E , E , which then admit air pressure from the compressed air chamber A , R , under the pistons of the valves E , which pistons are thereby raised thus shutting off the combustion tubes D until after the first explosion has taken place, a valve E^3 being provided in a pipe connection between the receiving chamber R and the air compressor A , so as to enable the pressure in the receiver R when restarting to be used for starting to drive the air compressor A , the two way valves E being then reversed to form connection with the explosion chambers and the valve E closed all by the operator, after the first explosion has taken place.

When the pressure in the receiving chamber R has reached a predetermined maximum it lifts the plunger or piston of the safety valve G sufficiently to allow the lever G^1 to engage with the piston rod C^6 at H^1 , thereby preventing the carburetor C from operating until the pressure in the receiving chamber R has reached a predetermined minimum, the lever G^1 for this purpose being pivoted at G^2 to the fixed part of the valve, and having a fork head G^3 engaging with the top of the piston whereby upon the rising of the piston the end of the lever G^1 engages with one of the notches H^1 in the rod on the carburetor piston when the rod C^6 is in the raised position.

An outlet K from the receiving chamber R is provided and adapted for being connected up to the distributing system. Suitable springs are provided in the carburetor C and piston valves D^{12} and E to operate in the reverse direction to that of the pressure of the combusted gases or compressed air as the case may be, and such springs are provided with suitable adjusting screws for the purpose of adjusting the springs to suit the required timing, while the space in the cylinder at the head of the piston of the valves E is provided with a valve to allow of the release of the pressure, and thus allow the valve E to open.

The piston D^1 is provided with a spring sleeve D^7 which is split, so as to have frictional contact with the inside of the cylinder of the valve, such spring being adapted to be carried up by the piston D^1 , in such a manner, that after the port D^3 and D^5 has been momentarily connected, the port D^3 is closed by the sleeve D^7 which port D^3 remains closed during the downward passage of the neck D^{15} of the valve past the position of the port D^3 , thus preventing air pressure from operating the carburetor dur-

ing the downward stroke of the piston D¹. The valve D⁸ is so arranged as to enable the pressure of the gases under the piston D¹ to be regulated.

5 Suitable stop valves S and S' are provided in the pipe connections to the compressed air chamber, so as to prevent any leakage of the pressure in the chamber or possibility of operation of the apparatus 10 when such operation is not required.

The explosion chambers which may be two or more in number, may be all arranged either inside or outside the receiving chamber, or part of the number of explosion 15 chambers used may be contained within, and part of such number outside the receiving chamber.

In cases in which it may be proposed for 20 the fuel charges to be of inflammable gas, such as coal gas, the arrangement for the supply of the gas to the piston C² would be suitably enlarged to allow for the passage 25 of the increased volume of the gas.

What I claim as my invention and desire 25 to secure by Letters Patent is:—

1. An apparatus for generating combustion products under pressure, including combustion chambers, means for supplying fuel charges to said combustion chambers, a 30 valve controlled chamber receiving the main products of combustion, a compressed air chamber, means controlled by pressure in the combustion chambers for establishing communication for the latter with said fuel 35 supply means, and means for mixing air from said compressed air chamber with the fuel charges to form the vaporized charge.

2. An apparatus for generating combustion products under pressure, comprising 40 combustion chambers, means for supplying fuel charges to said combustion chambers, a valve controlled chamber receiving the main products of combustion, a compressed air chamber, means controlled by pressure in 45 the combustion chambers for establishing communication for the latter with said fuel supply means, and means for utilizing the gases remaining in the combustion chambers to maintain the pressure in the compressed 50 air chamber.

3. An apparatus for generating combustion products under pressure, comprising combustion chambers, means for supplying fuel charges to said combustion chambers, a 55 valve controlled chamber receiving the main products of combustion, a compressed air chamber, means controlled by pressure in the combustion chambers for establishing communication for the latter with said fuel 60 supply means, and means for utilizing the pressure in the compressed air chamber for starting the apparatus.

4. An apparatus for generating combustion products under pressure, comprising 65 combustion chambers, means for supplying

fuel charges to said combustion chambers, a valve controlled chamber receiving the main products of combustion, a compressed air chamber, means controlled by pressure in the combustion chambers for establishing 70 communication for the latter with said fuel supply means, and an air compressor receiving the gases remaining in the combustion chamber and discharging the same into said compressed air chamber. 75

5. An apparatus for generating combustion products under pressure, comprising combustion chambers, means for supplying fuel charges to said combustion chambers, a valve controlled chamber receiving the main 80 products of combustion, a compressed air chamber, means controlled by pressure in the combustion chambers for establishing communication for the latter with said fuel supply means, an air compressor receiving the gases remaining in the combustion chamber and discharging the same into said compressed air chamber, and means for utilizing the pressure in the receiving chamber for starting operation of said air com- 85 pressor. 90

6. An apparatus for generating combustion products under pressure, comprising combustion chambers, means for supplying fuel charges to said combustion chambers, a valve controlled chamber receiving the main products of combustion, a compressed air chamber, means for mixing air from 95 said compressed air chamber with the fuel charges, and means for heating the compressed air by passing the same around the control valve in said receiving chamber. 100

7. An apparatus for generating combustion products under pressure, including a plurality of combustion chambers, means 105 for supplying fuel charges to said combustion chambers, a valve controlled chamber receiving the main products of combustion, and means for causing the combustion chambers to automatically fire alternatively 110 and in succession and for preventing a charging of the chambers until the pressure in the previously fired chamber has been exhausted.

8. An apparatus for generating combustion products under pressure, comprising combustion chambers, means for supplying fuel charges to said combustion chambers, a valve controlled chamber receiving the main products of combustion, a compressed air chamber, and a carburetor, the relative pressures of the combustion and compressed air chambers operating said carburetor to control the fuel and air supply to the combustion chambers. 115 120 125

9. An apparatus for generating combustion products under pressure, comprising combustion chambers, means for supplying fuel charges to said combustion chambers, a valve controlled chamber receiving the main 130

products of combustion, and means controlled by pressure in the combustion chambers for establishing communication for the latter with said fuel supplying means, said combustion chambers being formed by tubes contained within said valve controlled chamber.

10. An apparatus for generating combustion products under pressure, comprising 10 combustion chambers, means for supplying fuel charges to said combustion chambers, a receiving chamber for the main products of combustion, a compressed air chamber, and a carbureter comprising a cylinder, a 15 double piston reciprocating in the cylinder and operated by pressure from said compressed air chamber, and a supplementary piston valve actuated by the pressure of the combustion chamber to control the pressure communicated to said double piston.

11. An apparatus for generating combustion products under pressure, comprising combustion chambers, means for supplying fuel charges to said combustion chambers, a 25 valve controlled chamber receiving the main products of combustion, a compressed air chamber, a vaporizer adapted to communicate with said combustion chambers, and a carbureter comprising a cylinder, a double 30 piston reciprocating in said cylinder and operated by pressure from said compressed air chamber, and a supplementary piston valve actuated by the pressure in the combustion chambers to control the pressure 35 communicated to the double piston, said supplementary piston valve being adapted to open and close the vaporizer.

12. An apparatus for generating combustion products under pressure, comprising 40 combustion chambers, means for supplying fuel charges to said combustion chambers, a valve controlled chamber receiving the main products of combustion, a compressed air chamber, and a carbureter comprising 45 a cylinder, a double piston reciprocating in said cylinder and operated by the pressure from said compressed air chamber, a supplementary piston valve actuated by the pressure of the combustion chambers to control the pressure communicated to said double piston, and a lever connection to the magneto adapted to be tripped by said double piston.

13. An apparatus for generating combustion products under pressure, comprising 55 combustion chambers, means for supplying fuel charges to said combustion chambers, a receiving chamber for the main products of combustion, a piston device connected to 60 said receiving chamber, a lever stationarily arranged on said piston device, a carbureter having a reciprocating double piston, and a trip lever on said carbureter adapted to establish ignition, said carbureter and trip lever being held out of operation upon an ex-

cessive pressure in the receiving chamber operating said piston device and lever.

14. An apparatus for generating combustion products under pressure, comprising combustion chambers, means for supplying fuel charges to said combustion chambers, a receiving chamber for the main products of combustion, a compressed air chamber, an air compressor adapted to utilize the gases remaining in the combustion chambers 75 to maintain the pressure in the compressed air chamber, said air compressor being connected with said combustion chambers by tubes, and a valve in said tubes adapted to be closed by the pressure of the 80 burnt gases from the combustion chamber in which the preceding explosion has taken place.

15. An apparatus for generating combustion products under pressure, comprising 85 combustion chambers, means for supplying fuel charges to said combustion chambers, a receiving chamber for the main products of combustion, a compressed air chamber, an air compressor adapted to utilize the 90 gases remaining in the combustion chambers and to maintain the pressure in the compressed air chamber, said compressor being connected with said combustion chambers by tubes, a valve in said tubes adapted to be 95 closed by the pressure of the burnt gases from the combustion chamber in which the preceding explosion has taken place, a pipe connecting said valves with said compressed air chamber, and a manually operable valve 100 in said pipe to admit air pressure to said first named valves for starting the apparatus.

16. An apparatus for generating combustion products under pressure, comprising 105 combustion chambers, means for supplying fuel charges to said combustion chambers, a receiving chamber for the main products of combustion, a compressed air chamber, an air compressor adapted to utilize the 110 gases remaining in the combustion chambers and to maintain the pressure in the compressed air chamber, said air compressor being connected with said combustion chambers by tubes, a valve in said tubes adapted 115 to be closed by the pressure of the burnt gases from the combustion chamber in which the preceding explosion has taken place, a pipe connecting the receiving chamber with said air compressor, and a valve in said pipe 120 by which the pressure in the receiving chamber may be utilized for starting the air compressor to work.

In witness whereof I have hereunto set my hand in the presence of two witnesses.
